Atty.

UNITED STATES PATENT OFFICE.

GEORGE STEVENSON, OF TORONTO, ONTARIO, CANADA.

HOUSE CONSTRUCTION.

Application filed July 21, 1924. Serial No. 727,292.

The principal objects of the invention are, to enable the rapid construction of fire proof buildings, particularly of the small type used for dwellings or store houses, and 5 to devise a structure which will be easy to assemble and will produce a very strong and rigid structure.

The principal feature of the invention consists in the novel construction of boards 10 of concrete shaped to overlap and having a longitudinal tongue projection on the inner side adapted to interlock with notched supporting members, and whereby the bottom edges of the roof structures are formed 15 with integral gutters.

In the drawings, Figure 1 is a perspective section of a portion of a building constructed in accordance with this invention.

Figure 2 is an enlarged detail of one of 20 the boards.

Figure 3 is an enlarged detail of a modified structure of board with a longitudinal sloping gutter strip.

Figure 4 is a perspective detail in part 25 section showing a modified means of fastening the boards in place.

In the building of small houses, storage sheds and all such like structures it has been common to construct them of wood which 30 are not only subject to the danger of fire but as they are usually constructed from rather green lumber, they are practically uninhabitable very shortly after they are built and they are required to be covered.

The present invention contemplates a 35 structure where there will be no shrinkage to take care of. The structure will be weather proof and will be very easily assembled. It consists of in erecting a suitable frame work and providing on the frame work posts or studs 1 and rafters 2 for the roof structure, provided with external notches 3 which are preferably cut with a 40 downward slope.

Boards 4 are constructed of concrete, 45 preferably having a wire mesh reinforcement 5 therein and on the inward side they are formed with a longitudinal rib 6 which is sloped downwardly at an angle corresponding to the angle of the notches 3 in 50 the posts and rafters.

The upper edges of the board are preferably formed with an offset 7 on the outer side and the lower edges are formed with 55 an offset 8 on the inner side, thus providing

an overlap for the boards when assembled in the structure which will provide an efficiently weather tight joint so that water will not leak through the joint.

In the construction of boards for the 60 roofs of buildings, special boards are formed for the lower edges, as illustrated in Figure 1 in which the bottom edge is shaped to form a gutter 9 to receive and carry off the rain falling on the roof. 65

An important feature in connection with this bottom structure is that diagonally arranged ribs 10 raised from the outer surface are provided to prevent snow sliding and to direct the water fall on the main 70 portion of the roof toward the end of the building.

A suitable cap structure 11 may be formed of concrete or other suitable material to close the meeting joint of the ridge of the 75 roof.

In the detail illustrated in Figure 3 a tongue and groove bevelled joint is illustrated as a modification from the structure 80 illustrated in Figures 1 and 2.

In Figure 4 a slight modification for vertical work for the sides of a building is shown where short lengths of iron are bedded in the concrete structure. These 85 strips project from the inner sides of the board and may be nailed to the vertical supports. The boards will of course be made in various lengths and building structures can be standardized to use the standard 90 lengths without any necessity of cutting.

To erect a building of such material will be very simple, it being merely necessary to build the frame placing the notched vertical and rafter members at the outer sides and then simply laying the concrete boards in 95 place.

The angle rigs on the back interlock with the supports and each board placed in position over the other secures it firmly in position.

The fastening strips illustrated in Figure 4 may be used as an auxiliary means for securing the boards in place, if so desired.

What I claim as my invention is:—

1. A building structure, comprising a plurality of structural frames spaced apart and each having a plurality of spaced notches in their outward sides, boards formed of concrete extending horizontally between and bridging said frames, and longitudinal ribs 105

arranged on the inner side of said concrete boards adapted to enter said notches to secure the boards to said spaced frame.

2. A building structure, comprising a plurality of structural frames spaced apart and each having a plurality of notches formed in their outer sides, and arranged at an acute

angle to said outward sides, and boards of concrete extending longitudinally and bridging the space between said frames, each having acute angularly disposed ribs extending longitudinally of the inner faces thereof adapted to interlock with said notches. 10

GEORGE STEVENSON.
